(57) **CLAIM**

The ornamental design for a vertical electrical connector, as shown and described.

DESCRIPTION

FIG. 1 is a top, left, front perspective view of a first embodiment of a vertical electrical connector showing our new design;

FIG. 2 is a bottom, right, rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof;

FIG. 8 is a right side elevation view thereof;

FIG. 9 is a top, left, front perspective view of a second embodiment of a vertical electrical connector showing our new design;

FIG. 10 is a bottom, right, rear perspective view thereof;

FIG. 11 is a front elevation view thereof;

FIG. 12 is a rear elevation view thereof;

FIG. 13 is a top plan view thereof;

FIG. 14 is a bottom plan view thereof;

FIG. 15 is a left side elevation view thereof; and,

FIG. 16 is a right side elevation view thereof.

The broken line in the drawing is for the purpose of illustrating unclaimed environment only and forms no part of the claimed design. The dash-dot line represents the boundary of the claimed design.

In a preferred embodiment, the nature of this product is an electrical component that can take the form of a vertical electrical connector, such as a vertical backplane electrical connector, a leadframe assembly therefor, an electrical ground shield therefor, electrical contacts arranged therefor, an electrical contact therefor, a leadframe housing and electrical contacts therefor, and a connector housing therefor.

1 Claim, 10 Drawing Sheets
